UNITED STATES PATENT OFFICE

ALFRED ORDE TATE, OF TORONTO, ONTARIO, CANADA

SCANNING DISK

Application filed July 17, 1930. Serial No. 468,521.

This invention relates to scanning, and more particularly to a scanning system in which the image is completely scanned in more than one revolution of the scanning element.

The invention is particularly applicable to a system utilizing a scanning disk and provides for scanning a portion of the image during one revolution of the disk and a different portion in the next successive revolution of the disk. If the image is divided into two parts the arrangement is such that alternate halves of the image are scanned during successive revolutions of the scanning disk.

For the above purpose a shutter mechanism is provided in conjunction with the scanning disk which reveals only a portion of the image at any one time. The shutter may be arranged so that alternate halves of the image are revealed during successive revolutions of the scanning element, or so that a portion only of the image is revealed which corresponds to the instantaneous position of the scanning ray.

The present invention is particularly useful in scanning large images or in scanning a small image with a large number of scanning channels and permits the same to be accomplished without unduly increasing the size of the scanning disk, or in the case of a standard size image and a standard scanning system permits the size of the scanning disk to be materially reduced.

The invention will be particularly described as applied to a system involving a disk for simplicity of description. It will be obvious, however, that various other scanning systems may be employed within the scope of the invention. It is also to be understood that the number of scanning sections may be varied and that applicant is not limited to a device which completely scans the image in every two revolutions.

The invention also consists in certain new and original features of construction and

combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is an elevation of a scanning disk constructed in accordance with the present invention;

Fig. 2 is a front elevation of a shutter mechanism adapted to be used therewith;

Fig. 3 is a side elevation of the shutter mechanism showing its relationship to the disk;

Fig. 4 is a longitudinal section of the commutator;

Fig. 5 is a section taken on the line 5—5 of Fig. 4;

Fig. 6 is an elevation of a modified form of scanning disk;

Fig. 7 is a front elevation of a modified form of shutter; and

Fig. 8 is a side elevation of the shutter of Fig. 7 associated with a scanning disk.

Like reference characters denote like parts in the several figures of the drawings.

In the following description and in the claims parts will be identified by specific names for convenience, but they are intended to be as generic in their application to similar parts as the art will permit.

Referring to the drawings more in detail the scanning element shown in Fig. 1 comprises a disk 10 which is divided by a plurality of concentric circles into a plurality of equal concentric areas 11 and is also divided by a plurality of radii into equal radian spaces 12. An image 13 is adapted to be scanned by a plurality of apertures which

extend from an aperture 14 located in the outer concentric area to aperture 15 which is located in the inner concentric area. Each successive aperture around the disk is disposed 5 placed one concentric area from the preceding aperture, the system forming in effect a two revolution spiral beginning at the outer edge of the image and ending at the inner edge. It is to be noted that each of the apertures 10 is bounded by concentric circles and by radii of the disk. The apertures are accordingly keystone in shape and are of an area which varies directly as their distance from the center of the disk. This area is so located 15 that the total amount of light applied to the image by each of the apertures is the same. This is essential in order to secure a uniform definition of the image and is necessitated by reason of the fact that the speed of the 20 apertures is directly proportional to their distance from the center of the disk.

In the above described disk it will be noted that beginning in the position shown, one revolution in a clockwise direction serves to 25 completely scan the upper one-half of the image and the next revolution will serve to completely scan the lower one-half of the image. Inasmuch as there are two apertures in register with the image at any given time 30 it is necessary to provide a shutter mechanism which will render only one of said apertures operative. This mechanism is disclosed in Fig. 2 and comprises a frame 20 carrying a plurality of slides 21 and 22. Said frame includes an aperture 23 which is adapted to register with image 13. Each set of slides 21 and 22 closes one-half of the aperture and exposes the other half to the action of the scanning ray. Suitable channels 24, 25 and 35 40 26 are provided on frame 20 to permit slides 21 and 22 to have unimpeded movement.

For operating said slides a pair of pivoted levers 27 are mounted on frame 20 and are connected at their ends with slides 21 and 22 respectively by links 28 and 29. Said levers are operated by a solenoid 30 which cooperates with cores 31, said cores being connected to levers 27 by means of links 32. The arrangement is such that when solenoid 30 is energized cores 31 are drawn inwardly causing pivotal movement of levers 27 thereby opening slides 21 and closing slides 22. When solenoid 30 is deenergized a suitable 50 resilient means, such as spring 33 (Fig. 3) is associated with each of said levers 27 to cause a reverse operation, withdrawing cores 31 from solenoid 30, closing slides 21 and opening slides 22 thereby returning the apparatus 55 to the position shown in Fig. 2.

For operating solenoid 30 there is provided a commutator illustrated in Figs. 4 and 5 comprising a shaft 35 journaled in a housing 37 and carrying drum 38 of insulating material on which an arcuate commutator segment 39 is mounted. Said commutator 39 is

electrically connected to shaft 35 as by screw 40 which extends through said commutator and into said shaft.

A brush 41 is mounted in a suitable brush holder 42 which is insulated from housing 37 and secured therein as by insulating cap 43. Said brush is resiliently pressed against commutator 39 by spring 44 and is associated with an external binding post 45 by means of which it is connected to an external circuit. The circuit through solenoid 30 is completed by connecting the central portion of the solenoid to binding post 45 and connecting the two ends of the solenoid to an insulating binding post 46 which is mounted on frame 20. Said binding post 46 may be connected to one side of a battery 47, the other side of which is grounded to frame 20 by being connected to screw 48. The circuit is accordingly complete from battery 47 to binding post 46, solenoid 30, binding post 45, brush 41, commutator 39, shaft 35, frame 20, screw 48 and thence back to the battery 47.

The above shutter mechanism is mounted as illustrated in Fig. 3 adjacent scanning disc 10 which is carried on a suitable shaft 50. Said shaft also carries a sprocket wheel 51 which is connected by chain 52 to a sprocket wheel 53 which is mounted on shaft 35 of the commutator assembly. The sprocket wheels 51 and 53 are so related that the shaft 35 makes one revolution for each two revolutions of shaft 50. Commutator 39 is of such dimension that contact with brush 41 is completed through a one-half revolution of shaft 35 only. Accordingly, solenoid 30 will be energized during alternate one-half revolutions of shaft 35 and during alternate revolutions of disc 10. Slides 21 and 22 will 100 thus be alternately closed during successive revolutions of disc 10.

It will be evident that by properly selecting the arrangement of the elements and the size of aperture 23, the device may be so designed that the upper half of image 13 will be exposed for scanning during one revolution of disc 10 and the lower half will be exposed for scanning during the next revolution thereof. It is obvious that the number of sections into which the image is divided may be varied as desired, and the number of complete revolutions of the scanning disc for a complete image may be correspondingly altered. Shaft 35 must be so adjusted with respect to shaft 50 that the solenoid operates between successive apertures so that overlapping of the apertures on the image is prevented.

It is to be noted that the disk of Fig. 1 is arranged to scan an image progressively from top to bottom and that each time the scanning occurs in the same direction. This necessitates a rapid jump of the scanning ray from the bottom to the top of the image between successive scanings. The disc il-

illustrated in Fig. 6 provides for scanning the entire image in an undulating motion and eliminates abrupt changes in position of the scanning ray. For this purpose disc 60 of Fig. 6 is divided into a plurality of concentric areas and radial areas in the manner pointed out in connection with disk 10. The apertures of disc 60 begin at a central area 61 and extend to the outer area 62 thence returning to the central area 61 in a complete revolution of the disc. During the next revolution the apertures extend from area 63 which is adjacent area 61 to the inner area 64 and return to area 63. In two revolutions of the disc the scanning ray extends from the center to the top of the image thence to the bottom of the image and thence returns to the center and forms a complete cyclic or undulating motion. It is to be noted that the apertures are so arranged that the outer and inner sections are scanned twice in succession. This permits a uniform intensity of light to be applied to the various parts of the image inasmuch as all parts of the image are scanned twice in two revolutions of the disk. It is obvious that the shutter arrangement shown in Fig. 2 may be associated with disc 60, and arranged to operate in the manner described in connection with disc 10 so that alternate revolutions of the disks scan the upper portion of the image between areas 61 and 62 and the other revolutions of the disk scan the lower portion of the image between areas 63 and 64.

This undulating motion of the scanning ray permits the same to be more readily followed by the eye and eliminates eye strain by avoiding sudden changes in position of the ray.

A modified form of shutter which may be used in connection with disc 10 of Fig. 1 is illustrated in Fig. 7 and comprises a disc 70 having a spiral opening 71 formed therein. Said opening is of a width equal to the radial width of two or more apertures and, for example, may be made of a width equal to four concentric areas. Spiral 71 begins at the outer edge of the disc opposite aperture 14 and extends to a point 180° displaced therefrom and opposite the central aperture of Fig. 1. During the next 180° it extends from the point opposite the central aperture to a point opposite aperture 15 at the bottom of the image. The ends of spiral 71 overlap a certain amount to permit a rapid shift from aperture 15 to aperture 14 between successive scanning of the image. This overlap will not interfere with the operation of the disc inasmuch as no two apertures will be in register with the image and with spiral 71 at any one instant.

A method of mounting disk 70 is shown in Fig. 8. For this purpose disk 10 is secured to a shaft 50 as shown in Fig. 3 and is rotated thereby. Disk 70 is mounted on a sleeve 72

which is carried on shaft 50 and is driven by gear 73 which cooperates with an idler gear 74 mounted on an idler shaft 75. Said idler shaft is driven from shaft 50 by gears 76 and 77 which are constructed so that disk 70 makes one complete revolution for each two revolutions of disk 10. It will be evident that the arrangement of Fig. 8 provides a continuously movable shutter which so registers with the apertures of disk 10 that only one aperture is exposed to the image at any given time. The arrangement accordingly permits the apertures of disk 10 to be so arranged that more than one revolution of the disk is required to completely scan the image and yet prevents more than one aperture to be exposed to the image at any one time.

While the image 13 in the above system has been illustrated as keystone in shape for ease of description, it is obvious that a rectangular image may be obtained by employing a suitable aperture in conjunction with the scanning disk, and that in a disk of commercial size the relationship between the size of the image and the radius of the disk is such that only a slight keystone effect is obtained. It is contemplated, for example, that with a one inch image, a disk having a twelve inch radius would be employed and that at least forty-eight apertures will be used therein. It is obvious, however, that the size of the disk and the number and disposition of the apertures may be varied within wide limits.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A scanning system comprising a scanning element having apertures arranged to completely scan an image in two revolutions thereof, a shutter mechanism mounted independent of said element and adapted to alternately reveal portions of said image, means for operating said shutter mechanism comprising a solenoid, the arrangement being such that one-half of said image is revealed when said solenoid is energized and the other half is revealed when said solenoid is de-energized, a commutator for intermittently operating said solenoid and means for synchronizing said commutator with said scanning member whereby alternate halves of said image are revealed during successive revolutions of said member.

2. In a scanning system, a scanning member having a plurality of apertures therein adapted to successively reveal an object, a

shutter mounted independent of said member and in register with said apertures and adapted to reveal said object in sections, said shutter comprising slidable members, pivoted levers associated therewith, electrical means for operating said levers, and means for controlling said electrical means whereby different sections of said image are revealed in successive revolutions of said scanning member.

In testimony whereof I have hereunto set my hand.

ALFRED ORDE TATE.
